J. W. MOORE.

MANUFACTURE OF BLEACHING POWDER.

APPLICATION FILED FEB. 5, 1918.

1,272,880.

Patented July 16, 1918.

UNITED STATES PATENT OFFICE.

JOSEPH WILLIAM MOORE, OF RUNCORN, ENGLAND, ASSIGNOR TO CASTNER-KELLNER
ALKALI COMPANY, LIMITED, OF LONDON, ENGLAND.

MANUFACTURE OF BLEACHING-POWDER.

1,272,880.

Specification of Letters Patent. Patented July 16, 1913.

Application filed February 5, 1913. Serial No. 215,523.

To all whom it may concern:

Be it known that I, JOSEPH WILLIAM MOORE, a subject of the King of Great Britain, residing in Runcorn, England, have 5 invented certain new and useful Improvements in the Manufacture of Bleaching-Powder, of which the following is a specification.

In the manufacture of bleaching powder, 10 by causing lime and chlorin to pass through a rotating tube, or series of connected rotating tubes, it is of very considerable commercial and technical importance to obtain the gas issuing from the tube, free or almost free, from unabsorbed chlorin, while the maximum output of high strength bleach is being continuously produced.

Over forty years ago (see Henderson's British specification No. 3080 of 1871) it was 20 proposed to charge lime with chlorin by passing chlorin up inclined tubes or cylinders about 40 feet long, through which lime was made to travel by imparting rotation to the tubes or cylinders, or to screws inside them. The latter principle is embodied in the now well known apparatus, patented by Hasenclever in 1888, British specification No. 17012, but the rotating tube method, has so far as we know, hitherto, never been successfully attempted on the commercial scale.

Lunge in *Sulphuric Acid and Alkali*, vol. 111, page 468 (1896 edition) says:

"All mechanical bleaching powder chambers (other than Hasenclever's) hitherto erected have been abandoned after a short period of work, either because the machinery failed, or because the bleach came out weak or both."

Among the drawbacks to the before-mentioned proposals are that the shafts and cylinders rapidly corrode and the corrosion products mix with the powder decomposing same to some extent, impairing its keeping qualities and injuring its color, and 40 where scrapers or feeders are employed the powder is compressed against the cylinder wall forming an extremely hard and troublesome crust which has to be periodically chipped off involving much disagreeable and 45 expensive work. In addition to these drawbacks the gas issuing from such a rotating tube as described by Henderson contains a very considerable proportion of unabsorbed chlorin if a full output of strong bleach is

being produced and finally the working costs 55 are necessarily high.

According to my invention bleaching powder may be made of high strength in an inclined rotating cylinder which in respect of length may be compared with the tube 60 mills used in cement works. The best length appears to be about 80 feet, which is double that suggested in Henderson's aforesaid specification. The necessity for this great length is chiefly owing to the need for 65 thorough stirring of the partially chlorinated lime as it descends the cylinder and more particularly is it needed that the stirring should be prolonged while the material is in the presence of the most concentrated 70 chlorin, namely in the lower half of the length of the cylinder.

Mere lengthening of the cylinder as compared with Henderson's suggestion does not, however, insure a satisfactory product or 75 fulfil the requirement that the chlorin must be substantially completely absorbed. It being necessary to work on the counter-current principle the chlorin must be admitted at the bottom of the cylinder and there is 80 considerable difficulty in causing the chlorin to travel up the cylinder unless it is under such pressure that leakage from the cylinder cannot be avoided. This difficulty is overcome in my invention by connecting an outlet at the top of the cylinder with a suction power so as to maintain a slight suction in 85 the cylinder.

Without limiting myself to an exact 90 minimum length I may say that for satisfactory results a rotating tube not much shorter than 80 feet must be used. A suitable inside diameter is 20 inches. Such a tube or cylinder is illustrated in the accompanying drawings, in which Figure 1 is a 95 longitudinal section and Fig. 2 an end elevation.

The cylinder *a*, made in cast iron sections bolted together, as at *b*, is mounted in well-known manner on roller bearings *c* at an appropriate inclination, say 1 in 24. It is caused to rotate by worm gearing *d* at the rate of, say, thirty revolutions per hour. The cylinder is lined with glazed earthenware tiles *x*. It is connected at its ends by 100 means of glands *e* with stationary boxes *f*, *g* respectively. The box *f* has an opening *h* for exhaust of gases and an opening which 105

is connected by a short pipe *i* with the air-tight casing *k* of a helical conveyer *l*; the latter is rotated by gear *m* from the cylinder *a* and conveys the lime from hopper *n* to pipe *i* down which it falls onto an inclined chute *o* and then into the cylinder *a*. The lime in the helical conveyer *l* forms a sufficiently gas-tight packing. A suitable rate of feed of the lime in an apparatus of the dimensions here given is about 8 tons per week in warm weather and 10 tons per week in cold weather. The box *g* has an upper opening *p* for admission of gases and the lower opening connected with a pipe *q* closed at its lower end by a slide *r* which is opened intermittently to permit the finished bleaching powder to fall into the cask *s*. Inspection doors *t* are provided in the cylinder *a*. The boxes *f* and *g* have laterally extending brackets *u* supported by posts *v* carried by brackets *w* on the uprights which carry the end roller bearings *c*.

The exhaust opening *h* in the box *f* is con-

nected with a suction pump so as to draw the gases away from the apparatus and 25 maintain a slight suction therein, to assist the upward travel of the chlorin and prevent escape of chlorin.

Having thus described the nature of the said invention and the best means I know 30 of carrying the same into practical effect, I claim:—

A process for the manufacture of bleaching powder, which consists in causing lime to travel down an inclined rotating tube about 35 80 feet long and causing chlorin to travel up the tube by applying a slight suction at the upper part of the tube.

In testimony whereof I have signed my name to this specification in the presence of 40 two subscribing witnesses.

JOSEPH WILLIAM MOORE.
